(57) **CLAIM**

The ornamental design for a soft tissue compression shield, as shown and described.

DESCRIPTION

FIG. 1 is a top perspective view of a soft tissue compression shield in accordance with the invention;

FIG. 2 is a top elevational view of the tissue compression shield of FIG. 1;

FIG. 3 is a bottom elevational view of the tissue compression shield of FIG. 1;

FIG. 4 is a left elevational view of the tissue compression shield of FIG. 1;

FIG. 5 is a right elevational view of the tissue compression shield of FIG. 1;

FIG. 6 is a rear elevational view of the tissue compression shield of FIG. 1; and,

FIG. 7 is a front elevational view of the tissue compression shield of FIG. 1.
